Des. 218,889
Patented Oct. 6, 1970

218,889

BEACH CHAIR

Thomas L. Lamb, 36 Wellington, St.,
Toronto, Ontario, Canada

Filed Jan. 6, 1969, Ser. No. 15,209

Term of patent 14 years

Int. Cl. D6—01

U.S. Cl. D15—11

FIG. 1 is a side elevational view of a chair showing my design.

FIG. 2 is a front perspective view thereof.

FIG. 3 is a back perspective view thereof.

The essential features of the chair reside in the full line portions.

I claim:

The ornamental design for a beach chair, as shown and described.
